FLOTATION MACHINE

Arthur J. Weinig, Golden, and Roderick D.
Renner, Denver, Colo.

Application August 1, 1939, Serial No. 287,718

15 Claims. (Cl. 261—93)

This invention relates to improvements in aeration apparatus and more particularly relates to an improved impeller for flotation machines.

The present invention is a specific form of the impeller construction described and claimed in the co-pending application of Arthur J. Weinig, Serial No. 280,595, filed June 22, 1939, for Aerating method and apparatus. The operating methods and generic structural arrangements disclosed in that application are the sole invention of Arthur J. Weinig and such features are not claimed herein.

In the aforesaid application, there is disclosed a method of flotation operation in which material ejected from a rotary impeller is caused to ascend in a zone adjoining the confines of the flotation cell, while solids not elevated by the flotation reaction and which separate out of suspension descend through a separate central zone for re-circulation through the impeller.

The present invention embodies this feature of operation and in the structures described and illustrated herein, the aforesaid circulatory movement is utilized to provide a zone of ascent for matter elevated by the aerating influences and reagent, which is not impeded by solids separating from suspension and descending under gravitational influence.

The aforesaid application also discloses a form of impeller in which two streams of pulp in superposed relation are ejected across the periphery by the centrifugal action of the impeller. Air under pressure in substantial quantities is introduced into the uppermost zone and mixed with entering pulp at and after entrance.

This stream or zone is subjected to the hydrostatic pressure of the central column of descent and therefore operates in overloaded condition.

The lowermost compartment operates in underloaded condition and at the peripheral discharge a partial vacuum formed therein as a result of such condition is satisfied by the excess pressure from the uppermost stream which causes at least a portion of such material to assume a downward trajectory at the periphery, inducing a high degree of impingement and mixing in the discharging streams.

Such feature is also embodied in the present invention, although some differences in operating method and structural arrangements are incorporated in the present invention to attain the desired objects.

The aforesaid application also discloses a method and means of inducing a high degree of aeration through the medium of a rotary im-

peller, permitting a reduction in horsepower requirements over present practice without impairment of the aerating efficiency. The present invention also incorporates such features.

It is an object of the present invention to provide aerating apparatus of simple, durable and economical construction which may be operated with high efficiency under relatively low power consumption.

A further object of the invention is to provide aerating apparatus which employs a controlled circulatory movement of fluid in the aerating operation and utilizes the controlled movement to aid the mixing function of the operation.

Another object of the invention is to provide a novel agitation operation for flotation pulps providing unimpeded rise of entrapped solids to the surface without impedance from solids settling from suspension in the pulp body.

Other objects reside in novel details of construction and novel combinations and arrangements of parts, all of which will appear more fully in the course of the following description.

To afford a better understanding of the invention, reference is made to the accompanying drawings, in the several views of which like parts have been designated similarly and in which:

Figure 1 is a side elevation of a flotation cell to which the present invention has been applied;

Figure 2 is an enlarged sectional view of the impeller construction illustrated in Figure 1;

Figure 3 is a side elevation of a modified form of flotation cell to which the present invention has been applied;

Figure 4 is an enlarged section of the impeller construction of Figure 3;

Figure 5 is a side elevation of a modification of the flotation cell of Figure 1; and

Figure 6 is a side elevation of a modification of the flotation cell of Figure 3.

Referring first to Figures 1 and 2, the flotation cell illustrated therein comprises a tank 8 divided by suitable baffles 9 and a grid element 10 into a lower agitation compartment 12 and an upper separation compartment 13. Pulp is introduced into the cell through a bottom inlet 14 which may be connected in any suitable manner, such as the conduit here illustrated, with any source of supply such as conditioning apparatus, a classifier or a preceding cell.

Froth collecting on the surface of the body of material under treatment is caused to overflow at the overflow lip 15 and passes into a suitable receptacle such as a launder (not shown). In order to control the froth depth in the cell, the

discharge of tailings from the cell is regulated, and to this end, there is provided an outlet 16 controlled by a float-actuated valve 17 which determines the liquid level in the cell. A rotary shaft 18 driven in any suitable manner extends into the cell and carries at its lower end a rotary impeller 19.

Gas under pressure is carried in a header 20 supported on the tank 8 and connected with one or more conduits 21 which extend downwardly into the cell and terminate in nozzles 22 extending into a central opening 19a in the upper portion of the impeller 19. Gas under pressure is delivered to the impeller through the header 20 and conduits 21 and the volume of gas so admitted is controlled through the medium of valves 23.

Some operations will necessitate the introduction of reagent directly into the cell in preference to a preliminary conditioning treatment and the agitating and aerating influences of the machine are utilized for mixing the reagent. To this end, a reagent feeder is incorporated in the cell structure and comprises a funnel 24 located above the overflow level of the cell and a conduit 25 extending from the funnel into the opening 19a and terminating in a discharge outlet located in proximity to the discharge nozzles 22.

The impeller 19 of the present invention has top and bottom plates 19b and 19c respectively, which are separated by a dividing member or partition 19d extending from a hub member 19e approximately midway between the top and bottom plates.

The dividing member 19d is provided with a central opening 19n adjacent the hub 19e, and this arrangement permits a portion of the pulp entering the impeller through the opening 19a to pass below the dividing member into the lowermost discharge compartment B, while the remaining pulp entering through opening 19a passes through the upper compartment A to the peripheral discharge.

In order to maintain a balanced relation in the distribution of feed entering through opening 19a, this opening is of substantially larger diameter than the diameter of the opening 19n to compartment B. As a consequence, only a limited proportion of the feed admitted to the impeller passes through the compartment B, while a sufficient quantity is admitted into compartment A to insure its operation in overloaded condition.

In conjunction with the arrangement of the central openings 19a and 19n, the gas discharge nozzles 22 terminate adjacent the dividing member 19d between the opening 19n and the periphery of the impeller. By this arrangement, little, if any, of the discharging gas is drawn into the pulp stream entering compartment B and while some slight amount of gas may be present in the recirculating pulp by reason of previous entrainment, the volume of pulp traveling through compartment B will contain at most only minor quantities of undissolved gas.

As a consequence, the streams in the upper and lower chambers closely correspond in composition with the corresponding streams described in the aforesaid Weinig application.

In order to insure proper movement of the material through the compartments A and B, vanes 19h are provided which exert an impelling action on the material delivered to these compartments and force a rapid movement thereof toward the periphery.

In such impelling action, the vanes 19h produce a substantial mixing action as an incident to the impelling movement, with the result that the streams brought into intermixture at the periphery have already undergone an appreciable degree of mixing before impinging and penetrating the static body of pulp beyond the impeller.

As this form of impeller does not utilize a suction action to draw material upwardly from the bottom of the tank into the impeller, it is advisable to provide the undersurface of the impeller with sweeping vanes 19m which pump material in through inlet 14 and move any solids tending to collect on the bottom of the tank outwardly toward the walls of the cell where the full force of the agitative action and peripheral ejection acts thereon to move the settled constituents into suspension.

As illustrated in Figure 1, the pulp entering through inlet 14 is caused to travel laterally along the bottom of the tank underneath the impeller, and beyond the periphery rises under the influence of the agitation, with a portion thereof recirculating back through the opening 19a of the impeller. In the impeller, the entering pulp divides into two streams of different volume. The stream of lesser volume passes down into compartment B and is caused to travel by the impelling influences under the centrifugal influence to a point of discharge at the periphery. The stream of larger volume enters compartment A and upon entrance is subjected to the mixing influence of gas under pressure discharged through nozzle 22.

Where reagent is introduced directly into the cell, the reagent discharge is preferably located as illustrated in Figure 2, with the conduit 25 terminating near the opening 19n and somewhat above the same. The separation and differential movement of the two streams occur adjacent the discharge end of conduit 25 with the result that some of the reagent passes with the stream entering compartment B, while the remainder is entrapped in the stream moving through compartment A and in the mixing action in such compartments is brought into thorough and intimate contact with the solid constituents of the pulp therein.

From the foregoing, it will be apparent that compartment B will operate in an underloaded condition as the opening 19n is not large enough to satisfy the volume requirements thereof, while compartment A, due to the greater diameter of the opening 19a under the influence of a hydrostatic pressure in the tank, operates in an over-loaded condition. This results in the formation of a partial vacuum in compartment B, which at the periphery is satisfied by the downward flow of pulp from compartment A, due to the excess pressure thereof.

The resulting impingement of the two streams causes the gas, solids and liquid, inclusive of reagent, to be brought into thorough and intimate intermixture which is further intensified and developed by reason of the resistance offered by the more or less static body of pulp beyond the periphery to the discharging intermixture.

Thereafter, the impelling force of the agitation and aeration causes the pulp stream to ascend in the tank along the confining walls thereof and the entrainment of the flotation reaction rise freely in this ascending column without impedance from material above. Matter held only in suspension and heavy enough

to separate from the pulp stream in its upper portion is drawn toward the central portion of the cell in which there is a descending column of liquid, due to the pumping action of the impeller and the provision of the central opening 19a.

As a consequence, solids separating out of suspension pass into the central zone of descent before returning to the agitation zone under gravitational influence, and this withdrawal of settling solids from the rising column prevents any impedance thereby which might serve to rupture the surface attachments of the bubbles in the flotation reaction.

The material carried to the surface under the aerating influences becomes entrapped in the froth and moves across the overflow lip 15 as a concentrate.

The form of the invention illustrated in Figures 3 and 4 is similar to that previously described, with the exception that the flotation cell in this form of invention has its feed inlet at some location other than the bottom, and as a consequence, the impeller preferably is located at some distance from the bottom to provide a larger zone of non-aerated liquid in the bottom of the tank, which in part is recirculated in its elevating movement by the agitation of the impeller through the opening 19a and back into the impeller for further treatment.

In the cell illustrated in Figure 3, the inlet and discharge control have not been illustrated, but since such cells are in general use and well-known in the art, the details of such control appear unnecessary. It will be understood that some provision will be made for regulating the liquid level in the cell and thereby control the depth of froth which passes over the overflow lip 15.

In each form of the invention illustrated, the flotation action is the same and the circulatory movement determined by the impeller 19 likewise is the same in each of these cells. While the funnel 24 and associated conduit have only been shown as applied to the form of cell illustrated in Figure 1, it will be understood that such structure may be employed in either form of cell wherever required.

In this connection, the feature of the previously identified Weinig application in utilizing the gas conduits 21 and reagent conduit 25 as a means of restraining any vortex tendencies at the impeller inlet 19a is also utilized in the present invention.

The form of the invention illustrated in Figure 5 illustrates another modification of the invention, which is productive of highly beneficial results in certain types of treatments. The cell of this form of the invention is substantially the same as the type illustrated in Figure 1, with feed to the cell provided by the inlet 14 at the bottom thereof. The grid element 18 preferably is omitted and a column 27 encloses shaft 18 and the pipes 21 and 25. This column has its lower terminus in close proximity to the top of impeller 19 and is of a diameter large enough to encompass the opening 19a into the upper portion of the impeller.

The upper end of column 27 terminates below the froth bed of the cell determined by overflow 15, and in the preferred form, a slidable collar 28 is mounted at the upper end of column 27 to vary the effective elevation thereof.

While the column may be mounted in any

suitable manner, it has been found convenient to mount it on the baffle structure 9 either by frictional engagement therewith or through the intermediary of any suitable fastening device 5 and thus insure its maintenance during operation in close proximity to the impeller 19 but out of frictional engagement therewith.

The provision of the column serves to afford a closer control of the circulatory movement and restrains any tendency toward cross currents within the liquid body, which might otherwise serve to co-mingle the ascending and descending streams.

It is intended that the descending stream of material in this form of the invention should not return valuable constituents responding to the flotation action, but only so much of the mineral content as is being maintained in a state of suspension below the froth bed and is not being carried into the froth by the flotation reaction.

The enclosure thus provided for the impeller inlet 19a is subjected to a strong pumping influence induced by the impeller, and if the enclosure is extended into close proximity to the froth bed, a vortex action will result which will draw down portions of the concentrate. Therefore, the provision of the collar 28 is of importance in providing for selective variation in the elevation of the conduit, to eliminate vortex tendencies and provide a means for density regulation in the upper portion of the pulp body. The pipes 21 and 25 serve to restrain any vortex tendencies at the upper end of column 27 and by proper location of the collar 28, vortex conditions can be effectively eliminated.

In the upper portion of the pulp body immediately below the froth bed, there will be a zone containing a relatively large percentage of mineral which has been partially and incompletely elevated by the flotation action and supplemented by the suspending tendencies of the agitation, which as the operation proceeds, will increase in density.

This zone of increased density impedes to some extent the efficient performance of the flotation reaction in that minerals ascending under the action of the gas will not freely penetrate such zone and carry into the froth, and while some of the mineral in the zone is further elevated by the penetration of the gas into the zone, much of the mineral content is not carried into the froth and consequently passes to the next treatment stage with the tailing rather than the concentrate.

By locating the top of the column at or near such zone, the suction influences of the impeller serve to draw in large quantities of such mineral content and return the same to the impeller for re-treatment and subsequent elevation into the froth. As a consequence, in certain treatments, such as the flotation of ores carrying relatively large quantities of middlings product which are imperfectly floated by the normal action, the provision of the column 27 in the cell serves to improve the metallurgical result.

The form of cell illustrated in Figure 6 is similar to that illustrated in Figure 3 and has associated therewith a column 27a provided with a collar 28 for varying its effective elevation. This column 27a is of a diameter less than the diameter of the opening 19a into the impeller and is mounted in the cell with its lower terminus in compartment A of impeller 19.

With this form of column, a portion of the impeller discharge recirculates back through the

opening 19a without rising into the upper portions of the cell and there mixes with pulp delivered through column 27a into compartment A and after being subjected to the aerating influences, is again ejected from the impeller in the manner heretofore described.

From the foregoing, it will be apparent that the feed supplied to the impeller through the columns 27 and 27a is split and distributed between the compartments A and B as in the other forms of the invention, and the treatment of the material within the impeller is, in all essential respects, the same as hereinbefore described.

It is also obvious to those skilled in the art that either form of column 27 or 27a may be applied to any of the various forms of cell construction here illustrated, and the application of the respective forms to the various cells in the drawings is intended only as illustrative and not as being limited to such forms.

While in the forms illustrated herein the dividing member 19d is shown as being of the same diameter as the top and bottom plates 19b and 19c respectively, it will be appreciated that whenever desired for any reason, the dividing member may be of a lesser diameter to induce a preliminary mixing within the confines of the impeller before discharge of the material across the periphery.

Likewise, the size of the vanes 19h may be varied, and while the arrangement illustrated is the preferred form, it is within contemplation of the invention that vanes of different sizes may be variably located within the passages A and B, and in fact, any vanes which serve to exert an impelling action on matter in the passages may be substituted for those illustrated herein.

The explanation of the relative diameters of the openings 19a and 19n demonstrates the effectiveness of the relationship in controlling the amount of material delivered to each of the passages A and B, and it will be understood that variations in the size of such openings may be resorted to to obtain different degrees of mixing and discharge.

Changes and modifications may be availed of within the spirit and scope of the hereunto appended claims.

What we claim and desire to secure by Letters Patent is:

1. In separating apparatus, a rotary mixing element comprising upper and lower chambers, separately open at the periphery of the element for the separate discharge of two currents of pulp into a mixing zone exteriorly of said periphery, both chambers having central openings in their upper surfaces to receive pulp in which the element is immersed with one of said openings in their upper surfaces of greater diameter than the other, means for introducing gas in excess of atmospheric pressure into the pulp at the central opening of greater diameter, and vanes in the chambers to accelerate outward movement of pulp through the peripheral openings thereof.

2. In separating apparatus, a rotary mixing element comprising upper and lower chambers, separately open at the periphery of the element for the separate discharge of two currents of pulp into a mixing zone exteriorly of said periphery, both chambers having central openings in their upper surfaces to receive pulp in which the element is immersed with the opening of the upper chamber of greater diameter than the opening of the lower chamber, means for introducing gas in excess of atmospheric pressure

into the pulp at the central opening of the upper chamber and between the central opening of the lower chamber and its periphery, and vanes in the lower chamber to accelerate outward movement of pulp through the peripheral opening thereof.

3. In aerating apparatus, a rotary hollow body having in its top an opening around its axis of rotation for admission of pulp, a dividing member in the body defining upper and lower chambers therein, and having a central opening for admission of pulp to the lower chamber, means for introducing gas under pressure into pulp entering the upper chamber through the top opening, and vanes in the lower chamber for impellent action on the pulp admitted thereto.

4. In aerating apparatus, a rotary hollow body having in its top an opening around its axis of rotation for admission of pulp, a dividing member in the body defining upper and lower chambers therein, and having a central opening of lesser diameter than the diameter of the top opening, means in the upper chamber at a side of the opening to the lower chamber for introducing gas under pressure into pulp entering the upper chamber through the top opening, and vanes in the lower chamber for impellent action on the pulp admitted thereto.

5. In separating apparatus, a rotary mixing element comprising upper and lower chambers, separately open at the periphery of the element for the separate discharge of two currents of pulp into a mixing zone exteriorly of said periphery, both chambers having upper central openings to receive pulp in which the element is immersed, means extending into the upper chamber through its central opening for introducing gas in excess of atmospheric pressure into the pulp entering therein, and vanes in the lower chamber to accelerate outward movement of pulp through the peripheral opening thereof.

6. In aerating apparatus, a rotary hollow body having in its top an opening around its axis of rotation for admission of pulp, a dividing member in the body defining upper and lower chambers therein, and having a central opening of lesser diameter than the diameter of the top opening, means in the upper chamber for introducing gas under pressure into the pulp in the upper chamber entering therein through the top opening, vanes in the lower chamber for impellent action on the pulp admitted thereto, and vanes on the underside of the impeller for exerting an impellent movement on matter exteriorly thereof.

7. Froth flotation apparatus, comprising a tank having a feed inlet and a discharge outlet determining a liquid level therein, a rotary impeller in the lower portion of the tank having upper and lower chambers provided with a central opening for the admission of pulp under hydrostatic pressure, means for supplying gas under pressure to said chambers through the central opening of the upper chamber, and a conduit having its inlet in the pulp body below the froth bed determined by the overflow and positioned to discharge into the central opening of the impeller.

8. Froth flotation apparatus, comprising a tank having a feed inlet and a discharge outlet determining a liquid level therein, a rotary impeller in the lower portion of the tank having upper and lower chambers provided with a central opening for the admission of pulp under hydrostatic pressure, means for supplying gas under pressure to said chambers through the central

opening of the upper chamber, and a conduit having its inlet in the pulp body below the froth bed determined by the overflow and terminating above and in close proximity to the impeller in encompassing relation to its central opening.

9. Froth flotation apparatus, comprising a tank having a feed inlet and a discharge outlet determining a liquid level therein, a rotary impeller in the lower portion of the tank having upper and lower chambers provided with a central opening for the admission of pulp under hydrostatic pressure, means for supplying gas under pressure to said chambers through the central opening of the upper chamber, and a conduit having its inlet in the pulp body below the froth bed determined by the overflow and extending into the impeller through the central opening thereof.

10. In aerating apparatus, a rotary hollow body having in its top an opening around its axis of rotation for admission of pulp, a dividing member in the body defining upper and lower chambers therein, and having a central opening for admission of pulp to the lower chamber, means for introducing gas under pressure into pulp entering the upper chamber through the top opening, and vanes in each of said chambers for impellent action on the pulp admitted thereto.

11. Froth flotation apparatus comprising a tank having a feed inlet and a discharge outlet determining a liquid level therein, a rotary impeller in the lower portion of the tank disposed to direct pulp upwardly along upright walls of the tank by its centrifugal action, a member dividing the impeller into superposed compartments, each having a central intake opening in its upper surface and a peripheral discharge outlet, means for introducing gas under pressure into the uppermost compartment of the impeller, and conductive means disposed in the tank in a position to collect a middlings product below the liquid level and return such product through the central impeller openings for additional aeration within the confines of the impeller.

12. Froth flotation apparatus comprising a tank having a feed inlet and a discharge outlet determining a liquid level therein, a rotary impeller in the lower portion of the tank disposed to direct pulp upwardly along upright walls of the tank by its centrifugal action, a member dividing the impeller into superposed compart-

ments, each having a central intake opening in its upper surface and a peripheral discharge outlet, means for introducing gas under pressure into the uppermost compartment of the impeller, means for delivering flotation reagent adjacent the intake of each of said compartments, and conductive means disposed in the tank in a position to collect a middlings product below the liquid level and return such product through the central impeller openings for additional aeration within the confines of the impeller.

13. In aerating apparatus, a rotary hollow body having in its top an opening around its axis of rotation for admission of pulp, a dividing member in the body of lesser diameter than the body defining upper and lower chambers therein, and having a central opening for admission of pulp to the lower chamber, means for introducing gas under pressure into pulp entering the upper chamber through the top opening, and vanes in the lower chamber for impellent action on the pulp admitted thereto.

14. In aerating apparatus, a rotary hollow body having in its top an opening around its axis of rotation for admission of pulp, a dividing member in the body defining upper and lower chambers therein and having a central opening for admission of pulp to the lower chamber, means for introducing gas under pressure into pulp entering the upper chamber through the top opening, and conductive means for reagent introduction having a discharge outlet terminating within the impeller and above the central opening of the dividing member.

15. In aerating apparatus, a rotary hollow body having in its top an opening around its axis of rotation for admission of pulp, a dividing member in the body defining upper and lower chambers therein, and having a central opening for admission of pulp to the lower chamber, means for introducing gas under pressure into pulp entering the upper chamber through the top opening, and conductive means for reagent introduction having a discharge outlet terminating within the impeller and above and adjacent the periphery of the central opening of the dividing member.

ARTHUR J. WEINIG.
RODERICK D. RENNER.
